SAFETY RAZOR

Anestis Foltis, Jackson Heights, N. Y., assignor of
one-fourth to Allan Panzer, New York, N. Y.

Substituted for application Serial No. 215,755,
June 25, 1938. This application May 21, 1946,
Serial No. 671,282

4 Claims. (Cl. 30—47)

1

This application is a substitute application for my application, Serial No. 215,755, filed June 25, 1938, now abandoned.

This invention relates to improvements in safety razors.

An important object of the invention is to provide an inexpensive safety razor having an integral razor blade whereby the entire razor must be disposed of after the blade becomes too dull for shaving purposes.

Another feature of the invention is a safety razor wherein the blade and its holder constitute a single unit which is simple and inexpensive in construction to enable its user to economically dispose of the entire unit after a limited number of shaves, thus eliminating the usual practice and annoyance of removing a used blade from its holder and replacing the same with a new one.

A further object of the invention is the provision of a safety razor unit in which the razor blade and holder is constructed from a single blank of bendable metal.

A still further feature of the invention is the provision of a razor blade holder in which the handle thereof is constructed of a pair of wing-like elements flexibly connected to the underside of the razor head to enable compact folding of the elements against the head for packing purposes, and which elements may be flexed outwardly and brought into confronting relation to handle forming position when the razor is to be used for shaving.

Other novel features of construction will be apparent as the following specification is read in conjunction with the accompanying drawings, in which:

Figure 1 is a plan view of one form of my invention wherein the blade is formed integral with the holder.

Figure 2 is a top plan view of the form of the invention shown in Figure 1, with the parts in operative relation.

Figure 3 is an enlarged vertical longitudinal sectional view on the line 3—3 of Figure 2.

Figure 4 is a vertical transverse sectional view on the line 4—4 of Figure 3.

Figure 5 is a plan view of a blank showing a somewhat modified form.

Figure 6 is a top plan view of the form shown in Figure 5 with the parts in assembled relation.

Figure 7 is an enlarged vertical longitudinal sectional view on the line 7—7 of Figure 6.

Figure 8 is a vertical transverse sectional view on the line 8—8 of Figure 7.

2

Figure 9 is a plan view of the blank of a further modified form.

Figure 10 is a vertical longitudinal sectional view of the form shown in Figure 9 with the parts in associated relation.

Figure 11 is a vertical transverse sectional view on the line 11—11 of Figure 10.

In connection with the invention herein, I have illustrated various embodiments of a safety razor in which the blade is formed integral with the holder, and each specific form of such construction will be described.

In the form illustrated in Figures 1 to 4 inclusive, the letter G designates a blank of bendable metal cut to provide a double edge cutting blade 90 at one end thereof, and to one end of which a clamping plate 91 is connected along the line of fold 92. Equidistantly spaced on opposite sides of the line of fold 92 are slots 93

and 94 respectively provided in the blade 90 and clamp 91. The clamping plate 91 is connected to a guard plate 95 along the line of fold 96, the guard plate having rows of spaced slots 97

inwardly of its longitudinal edges and the said edges are folded on the dot and dash lines 98 to provide guard teeth for the longitudinal sides of the guard plate. Struck out from the guard plate 95 is a prong 99 which is so located as to pass through the slots 93 and 94 when the parts are in folded position in the manner presently to be explained. Connected to the guard plate 95 along the line of fold 100 is an arm 101 to

which a finger piece or handle 102 is connected along the line of fold 103. In folding the blank G the blade 90 is folded over the clamping plate 91 on the fold line 92, thus causing the slots 93 and 94 to register. The clamping plate 91 is next folded on the line 96 which positions the blade 90 intermediate the clamping plate 91 and the guard plate 95.

The prong 99 is struck upwardly so as to pass through the aligned slots 93 and 94, after which the prong is bent over the clamping plate 91 as best illustrated in Figure 3. The arm 101 is folded beneath the guard plate 95 and secured by the slotted longitudinal edges of the guard plate. The handle or finger piece 102 may now be bent at right angle to the arm 101 to provide a finger grip for the holding of the razor when in use.

In Figures 5 to 8 inclusive, the razor is constructed from a single blank of bendable metal H which is cut to provide a double edge cutting blade 104 having a relatively large rectangular slot 105 provided therein. One end of the blade

104 is connected to one end of a guard plate 106

50

55

in Figures 5 to 8 inclusive, the razor is constructed from a single blank of bendable metal H which is cut to provide a double edge cutting blade 104 having a relatively large rectangular slot 105 provided therein. One end of the blade

104 is connected to one end of a guard plate 106

along a line of fold 107, the said guard plate having a centrally located H-shaped slot 108 to facilitate the outward striking of longitudinal prongs or flanges 109 which are intended to pass through the slot 105 when the blank is folded into razor forming position. Inwardly of the longitudinal edges of the guard plate 106 are rows of spaced slots 110, the longitudinal edges of the guard plate being foldable on the dot and dash lines 111 to form guard edges for the guard plate. Connected to the other end of the guard plate 106 along the line of fold 112 is a reinforcing plate 113 to which an arm 114 is connected along the line of fold 115. A finger piece 116 is connected to the arm 114 along the line of fold 117. In this form, the blade 104 is folded over the guard plate 106 along the line of fold 107, after which the prongs or flanges 109 are bent upwardly to extend through the slot 105 of the blade, the said prongs being bent outwardly in opposite directions as best illustrated in Figures 6 and 8. The reinforcing plate 113 is next bent under the guard plate 106 along the fold 112, after which the arm 114 is folded flat against the plate 113 along the line 115 and when the razor is to be used, the finger piece 116 is bent on the fold line 117 so as to extend at right angles from the arm 114 and provide the necessary finger grip for holding the razor when in use. The reinforcing plate 113 is held against the guard plate 106 by reason of the under folding of the longitudinal edges of the guard plate along the fold lines 111 and which folded portions lap the plate 113 as well as by reason of the prongs 113 being passed up through the opening in guard plate 106, resulting from flanges 109 being bent over blade 104, and being bent over onto blade 104, as seen in Figures 6 and 7.

In Figures 9 to 11 inclusive, substantially the same construction as that shown in Figures 5 to 8 inclusive is provided, with the exception that in the preceding form, only one handle or finger element was provided. In order to provide the added finger grip element, the blank is formed with an arm 118 which is connected to one end of the blade 104 along the line of fold 119 and extending beyond the arm 118 is a finger element 120 foldable on the line 121. In this form of blank, the reinforcing plate 113 is first folded under the guard plate 106, thereafter the blade 104 is folded over the guard and locked thereto by the prongs or flanges 109, the arm 114 folded parallel to plate 113 and the finger element 116 is bent at right angle to the arm 114, after which the arm 118 is folded around and beneath the reinforcing plate 113 and the finger piece 120 bent at right angle thereto to coat with the finger piece 116 and provide the necessary finger grip for the user. Also in this form, the under bent longitudinal edges of the guard plate overlie the arms 114 and 118 as illustrated in Figure 11.

Whereas I have mentioned that the razor unit may be constructed of steel, I wish it to be understood that in instances where the blade is formed separate and joined to the holder, the holder may be constructed of sheet aluminum. Also, in instances where the blade is integral with the holder, the entire unit is constructed of steel but only the cutting blade is heat treated for sharpening purposes.

While I have shown and described what I consider to be the preferred embodiments of my invention, I wish it to be understood that other

modifications thereof may be resorted to as come within the scope of the appended claims.

I claim:

1. A razor comprising a bent strip with a guard section and a clamping section united to each other, a handle united to the guard section, a blade united to the clamping section, said blade and said clamping section being folded transversely of said strip to overlie the guard section with the blade between said sections, the handle being bent outward at the middle of the guard section, the guard section having securing means engaging the clamping section and blade.

15 2. A razor comprising a bent strip with a guard section and a clamping section united to each other, a handle united to the guard section, a blade united to the clamping section, said blade and said clamping section being folded transversely of said strip to overlie the guard section with the blade between said sections, the handle being bent outward at the middle of the guard section, the guard section having securing means engaging the clamping section and blade, said guard section having transverse slots along its lateral edges and being doubled over midway of said slots, lengthwise of said strip and away from said blade to form projections along the edges of the blade.

30 3. A razor comprising a bent strip having a blade adjacent one end and a handle at the other, a clamping section and another section united to each other between the blade and the handle, said blade and said clamping section being folded transversely of said strip to overlie the other section with the blade between said sections, the handle being turned to project outward at the middle of said sections and securing means engaging said blade and said other section.

35 4. A razor comprising a bent strip having a blade adjacent one end and a handle at the other, a clamping section and another section united to each other between the blade and the handle, said blade and said clamping section being folded transversely of said strip to overlie the other section with the blade between said sections, the handle being turned to project outward at the middle of said sections and securing means engaging said blade and said other section, one of said sections having transverse slots 40 along its lateral edges and being bent midway of the slots lengthwise and away from the blade to form projections along the edges of the blade.

ANESTIS FOLTIS.
